UNITED STATES PATENT OFFICE.

OBEDIAH SALLADY, OF LOS ANGELES, CALIFORNIA.

FUMIGATOR.

SPECIFICATION forming part of Letters Patent No. 588,090, dated August 10, 1897.

Application filed March 13, 1896. Serial No. 583,060. (No model.)

To all whom it may concern:

Be it known that I, OBEDIAH SALLADY, a citizen of the United States, residing at Los Angeles, in the county of Los Angeles and 5 State of California, have invented a new and useful Fumigator, of which the following is a specification.

My invention relates to those fumigators which are designed to force smoke into squirrel and gopher holes to asphyxiate and exterminate the animals therein. Incidentally my invention is capable of various other uses, it being of such great capacity that it can be employed effectively for fumigating trees when 15 said trees are inclosed in a tent or other like receptacle or for fumigating plants in the open air.

With the fumigators heretofore in use the smoke-chamber and the apparatus for producing the blast have been arranged in the form of a telescoping cylinder, with the blast-chamber directly above the smoke-chamber. Such devices are single action, or capable of producing a blast only in puffs and not continuously. In exterminating squirrels and gophers it is necessary to use materials producing noxious and stifling fumes—such materials, for instance, as sulfur, &c. When the smoke-chamber and blast-chamber are set 20 together, as has heretofore been the custom, it is impossible for the operator to escape from the fumes emitted by the machine, and hence found practically impossible to use with the ordinary fumigator materials which will 25 produce asphyxiation of the vermin without partially asphyxiating the operator. Another objection is that the volume of smoke produced by the single-action blast-machines is not sufficient, in many cases, to fill the burrows to such an extent as to destroy the vermin therein.

The object of my invention is to produce a device which will give a practically continuous flow and great volume of smoke and to 30 provide means whereby the operator may stand at a distance from the smoke-chamber while operating the machine and by paying due observance to the wind can always avoid the fumes which must necessarily escape in 35 small quantities from the joints of the smoke-chamber and through the crevices of the soil above the burrows.

A further object of my invention is to provide a device of this kind in which when it becomes necessary to fill the smoke-chamber 55 with fuel the nozzle can be removed and the fuel introduced from the nozzle end of the chamber, thus bringing the fire always upon the top of the fuel when the device is inverted for use.

My invention comprises the various features of construction and combinations of parts hereinafter set forth.

The accompanying drawings illustrate my 65 invention.

Figure 1 is a perspective side elevation of a machine embodying my invention. Dotted lines indicate the position of the nozzle of the smoke-chamber when the nozzle is swung upon its hinge to open the smoke-chamber to 70 allow fuel to be introduced thereto. Fig. 2 is a vertical mid-section of my improved air-pump for producing a continuous blast and of the smoke-chamber. Fig. 3 is a fragmental sectional view illustrating the construction of 75 my improved valve for the air-pump.

In the drawings, A represents the smoke-chamber, which is shown inverted from its position when in use and has its top a closed and has its lower portion a' tapered. The 80 nozzle A' is also tapered and fits upon the exterior of the tapered portion of the body of the smoke-chamber and is secured thereto by means of a hinge a'', so that such nozzle can be swung off of the smoke-chamber, as shown 85 in dotted lines in Fig. 1, thus to allow fuel to be placed in the smoke-chamber.

a''' represents a grating placed in the nozzle to prevent the fuel from passing so far into the nozzle as to restrict the passage of 90 the smoke therefrom. To the top of this smoke-chamber is attached a nipple B, and to this nipple is secured a hose C, the other end of which hose is secured to a nipple F', which projects from the air-chamber F of the 95 air-pump D.

The air-pump D consists of a cylinder D', which is secured to a base D'', which extends outward on each side of the cylinder and is adapted to receive the feet of the operator, so 100 that the operator can stand upon the base to hold the air-pump steady while he is operating the pump. This pump is provided at its bottom with an annular row of perforations

d, and above these perforations I arrange a partition *d'*. In the partition *d'* is arranged a valve *e*, and at the top of the chamber is arranged a valve *e'*. The valves *e* and *e'* are each adapted to allow air to enter the air-chamber and to prevent it from escaping therefrom when the plunger is operated. To one side of the air-pump cylinder I secure an air-chamber *F*, and at the top and bottom of the chamber I arrange valves *f f'*, which are each adapted to admit air from the cylinder into the air-chamber, but to prevent it from escaping from the chamber back into the cylinder.

15 *G* is the piston or plunger of the air-pump, and *G'* is the cross-piece or handle-bar for operating the same.

To the side of the air-chamber *F* and substantially near its mid-length is arranged a 20 nipple *F'*, which projects from the air-chamber and to which is secured one end of the hose *C*.

The construction of the valves *e* and *e'* is particularly illustrated in Fig. 3. These 25 valves each comprise the base member, which may be the partition, the head-plate *d'''*, or the side wall of the cylinder *D*, as the case may be, but which I have lettered *E* in Fig. 3, the flexible valve-plate *E'*, for which I have 30 ordinarily employed rubber, and a metallic guard-plate *E''*, offset to bring it away from the plane of the valve-opening *E'''*, which is provided in the base *E*. The guard-plate, the valve-plate, and the base member are all secured together by means of one bolt *e''*, whereby I produce a valve of exceedingly cheap and simple construction, and yet one which is very 35 efficient in operation.

In Fig. 2 I have shown a fragment of hose 40 *H*, secured to a nipple *H'*, which is fitted upon the tapering nozzle of the smoke-chamber, whereby to adapt the device for fumigating. By means of the hose *H* the fumes may be conducted into a tent or other device (not 45 shown) arranged inclosing the tree and the tent filled with fumes, thus destroying scale, &c. In fumigating plants I have found it to be unnecessary to inclose the plant in order to kill depredating insects.

50 In practical operation it has been my custom to manufacture the smoke-chambers of heavy Russian iron having double-lapped airtight seams. The cylinder of the air-pump and the air-chamber are ordinarily made of 55 galvanized iron, closed at its top by means of a cast head-plate *d''*, while the piston-rod and the actuating-handle are made of gas-pipe. The construction may be varied without departing from the spirit of my invention.

60 As shown in the drawings, the top of the smoke-chamber is resting upon the ground in the manner in which the device is arranged to set when not in use, but it is to be understood that when used for smoking squirrels 65 or gophers the nozzle of the smoke-chamber is inserted into the burrow and the dirt packed

tightly therearound to prevent the escape of smoke from the burrow.

In practice to prepare the device for use the smoke-chamber is inverted, as shown. 70 The nozzle is tilted upon its hinge, as shown in dotted lines in Fig. 1, and fire is introduced into the smoke-chamber. Then straw or other combustible material is placed in the smoke-chamber, together with sulfur or other material from which it is desired to produce the smoke and fumes. Then some damp straw or other suitable material is placed upon the top of that, the chamber being ordinarily 75 filled to the top of the tapering portion thereof. Then the nozzle is swung back into its closed position, as shown, and the device is ready for use.

When it is desired to recharge the smoke-chamber with fuel, since the top cannot be 80 removed from the chamber it is necessary to set the chamber upon the ground, as shown, the flat top serving as a base upon which it rests. This automatically brings the fire into such position that when the smoke-chamber 85 is charged with fuel and is again ready for use the fire will be arranged on top of the fuel in place of beneath it, as is the case in the fumigators heretofore in use and in which the fuel is introduced through the top of the 90 smoke-chamber.

By my improved double-action air-pump I am enabled to produce a continuous blast and to force an extraordinarily large volume of smoke from the smoke-chamber. In fact, 100 with one of my devices I can produce smoke in volume equal to that produced by an ordinary locomotive-engine.

By reason of the flexible connection between the smoke-chamber and the air-pump 105 the operator is enabled to stand at a distance from the smoke-chamber and to operate the air-pump without any liability whatever of being subjected to the noxious fumes generated in the smoke-chamber. 110

By arranging the nozzle so that it can be removed to open the base of the smoke-chamber I am enabled to make the top of the chamber air-tight, so that the only joint is the one where the nozzle joins the smoke-chamber. 115 By reason of the tapering form of the chamber and the nozzle the joint is made to fit so tightly as to be practically air-tight, so that no fumes can escape excepting from the nozzle of the smoke-chamber. 120

A'' represents a handle secured to the smoke-chamber, and *D'''* is a handle secured to the air-pump.

Now, having described my invention, what I claim as new, and desire to secure by Letters 125 Patent, is—

1. The fumigator set forth, comprising the smoke-chamber having its top closed and having its lower portion tapered; a nozzle tapered to fit upon the tapering lower portion of the 130 chamber and hinged to such chamber; an air-pump secured to a base; such base; project-

ing upon both sides of the pump-cylinder and adapted to receive the feet of the operator; and the flexible hose connecting the air-pump with the top of the smoke-chamber.

5 2. The fumigator set forth, comprising the smoke-chamber provided near its top with a nipple and having its lower end tapered; a nozzle, tapered to fit the lower part of the chamber and hinged to the body of the smoke-chamber; an air-pump comprising a vertical cylinder secured to a base and provided at its bottom with a series of air-inlets; a partition

arranged above the air-inlets; a valved inlet and outlet at both top and bottom, the outlets communicating with a discharge-chamber; 15 the nipple secured to the discharge-chamber; and a flexible hose connecting the nipple of the discharge-chamber with the nipple of the smoke-chamber.

OBEDIAH SALLADY.
